SANDING MACHINE FOR VEHICLES

Benjamin F. Atwood, Roxbury, Mass., assignor to
Marshall P. Marston, Winchester, Mass., as
trustee

Application May 29, 1940, Serial No. 337,779

8 Claims. (Cl. 291—29)

This invention relates to improvements in sanding machines for vehicles and the general object of the invention is to provide a sanding machine having controllable means for selectively discharging sand in the path of the tractive wheels of the vehicle which will be certain and effective in operation.

In usual sanding machines the discharge of sand from the sand box or tank containing the same is controlled by a sliding gate valve or by a poppet valve. Such valves are inefficient for the reason that sand is likely to enter between or accumulate between the relatively movable parts of the valve and valve seat so that the valve will stick and prevent its operation, or remain partially open thereby causing a waste of sand.

The present invention is designed to avoid these defects by providing an arcuate swinging closure member underlying and narrowly separated from the lower end of the outlet pipe and movable about an axis located above and laterally of the outlet end of the pipe thereby permitting the sand to flow freely from the outlet pipe.

A further object of the invention is to provide means operable upon or by the swinging movement of the closure member to jar or impart vibration to the outlet pipe thereby to dislodge any accumulation of sand which might have occurred within the outlet pipe, or above it.

Another object of the invention is to provide a flexible mounting for the outlet member in the bottom of the sand box thereby enabling the outlet pipe to be more effectively jarred or vibrated upon the opening of the closure member.

Another object of the invention is to provide a sanding machine of the character above described with a canopy of considerably larger diameter than that of the outlet pipe overlying the inlet end of the outlet pipe and adapted to support the majority of the weight of the sand above the outlet pipe and so supported from the bottom of the tank as to enable the sand freely to flow into the inlet end of the outlet pipe.

Another object of the invention is to provide an outlet pipe construction having an inlet end portion so constructed as to facilitate free flow of sand therethrough. This is accomplished in the present invention by providing the upper end of the pipe with an angularly inclined entrance presenting a larger area than the area of the horizontal section of the pipe and also forming the outlet pipe with an upper portion of somewhat less diameter than the lower portion and divergently tapering downwardly.

Another object of the invention is to provide novel means for actuating the closure member comprising a shaft fixedly secured to the arcuate closure member having an arm flexibly connected to the core of a solenoid which preferably is mounted upon the bottom of the sand box with

manually operable means for controlling from a convenient point, such as the dash board of a vehicle, the electric current supplied to the solenoid to energize it and thereby cause actuation of the closure member.

Another object of the invention is to provide removable cover mechanism for the sand box with means for effectively clamping and sealing the cover upon the sand box in such manner as to prevent entrance of water into the sand within the box.

Another object of the invention is to provide means for preventing water from splashing upon the closure member of the sand box or entering the casing surrounding the closure member.

A further object of the invention is to provide an effective means for detachably mounting the sand box upon suitable supporting means carried by the vehicle.

These and other objects and features of the invention will more fully appear from the following description and the accompanying drawing and will be particularly pointed out in the claims.

A preferred embodiment of the invention is illustrated in the accompanying drawing, in which,

Fig. 1 is a conventional illustration of a portion of the chassis and traction wheels of a vehicle with the sand box embodying the invention mounted in advance of and in proximity to the traction wheels;

Fig. 2 is a side elevation of the sanding machine for delivering the sand in proximity respectively to a pair of traction wheels, the lower portion of the sand box and closure mechanism being shown in vertical section and the central portion broken away to show that the sand box may be of any desired depth;

Fig. 3 is a vertical sectional view of the construction shown in Fig. 2 on line 3—3 viewed from the right toward the left;

Fig. 4 is a detailed vertical sectional view similar to the lower portion of Fig. 3, but showing the closure member swung to a position to permit discharge of sand from the sand box through a discharge opening in the casing into the path of a traction wheel; and,

Fig. 5 is a fragmentary detail view showing a modification of the means for sealing the cover on the top of the same box to prevent admission of water into the sand box.

A preferred embodiment of the invention is illustrated herein as applied to a vehicle such as a truck a portion of which is illustrated in Fig. 1 comprising a frame or chassis 1 and traction wheels 2 mounted upon the chassis in the usual manner (not shown) with a sand box 3 supported upon the chassis of the vehicle. In the particular construction illustrated in Fig. 1

the sand box 3 is of rectangular form comprising parallel sides 4 and parallel ends 5 and a bottom 6. The means for supporting the sand box upon the chassis of the vehicle desirably comprises 5 angle bars 7 which are welded or otherwise secured to the sides 4 of the sand box at a distance from its upper end and adapted to rest upon the horizontal flanges of complementary angle bars 8 which are mounted upon the chassis 10 and extend across it so that similar sand boxes may be mounted in front of the other traction wheels. The end of the box may be strengthened by plates 9 extending across and welded or otherwise secured to it intermediate 15 of the angle bars 7 and if desired may also be welded to the angle bars to provide a more rigid construction.

In order to prevent the entrance of water into the sand box a cover 10 is provided having a 20 downwardly extending peripheral flange 11 which closely embraces the upper end of the sand box and seats upon a water-repellent packing. As illustrated in Fig. 3 Z-bars 12 are secured to the sides and ends of the sand box preferably with 25 their lower edges engaging the horizontal flanges of the angle bars 7 and plate 9. These Z-bars provide channels which contain a water-repellent packing 13, such as rubber, which is engaged by the edge of the flange 11. A modified sealing 30 construction is shown in Fig. 5 in which a metal band 12x extends along the sides and ends of the sand box at a suitable distance from the top thereof and the vertical flanges of reversely positioned angle bars 7x and the end plates 9 over- 35 lie and extend above the band 12x sufficiently to provide a channel to receive the water-repellent packing which is engaged by the edge of the cover flange. The bands 12x, the angle bars 7x, and the plates 9 may be bolted, welded, or 40 otherwise secured to the walls of the sand box.

Any suitable means may be provided for clamping the cover upon the sand box. A simple and convenient device which is illustrated herein comprises a series of plates having inwardly inclined legs 14 the lower ends of which rest upon the horizontal flanges of the angle bars 7 and inwardly extending angularly inclined sections 15 which overlie the cover 10. Bolts 16, which are mounted in the horizontal flanges of the angle 45 bars 7, extend through suitable apertures in the inwardly extending portion 15 of the plates and preferably winged nuts 17 on the upper ends of the bolts serve as means for clamping the plates firmly against the horizontal flanges of the angle bars and the cover and to force the edge of the cover flange 11 tightly into engagement with the packing 13 thus effectively excluding the entrance of water into the casing.

60 One of the principal objects of the invention is to provide means for distributing sand from the sand box in the path of the traction wheels of the vehicle comprising an outlet pipe and closure member therefor which can be easily manipulated to close or open the outlet end of the outlet pipe which will be certain in operation and which will not be subject to sticking or choking by reason of accumulation of sand between the relatively movable parts thereof.

70 A further object of the invention is to provide means operable when the closure member is moved toward open position which will jar the outlet pipe or which can be repeatedly manipulated to jar the outlet pipe to dislodge any accumulation of sand in the outlet pipe which would

bridge or otherwise interfere with the free flow of the sand through the outlet pipe. This is accomplished in the present invention by providing a swinging closure member, preferably of arcuate form movable about a pivotal axis located 5 above the outlet end of the sand delivery pipe and laterally of the axis of the pipe, so constructed that when the closure member is swung to open position as to impinge upon and jar the pipe. In order to facilitate the jarring or vibrat- 10 ing movement imparted to it the outlet pipe desirably is mounted upon a flexible resilient member suitably supported upon the bottom of the sand box.

In the particular construction illustrated the 15 sand box is provided with two outlet pipes each of which is adapted to deliver sand in the path of the traction wheels, such for example as those of a pair of traction wheels commonly employed in heavy trucks.

20 These outlet pipes and the closure members therefor may be and preferably are identical and a description of one will serve for a description of both.

As illustrated each outlet pipe 18 extends 25 through an aperture 19 suitably positioned in the bottom of the tank and of greater diameter than the outlet pipe. The outlet pipe extends through and is fixedly secured to a flexible member 20 preferably a thin sheet of resilient metal 30 which overlies the aperture 19 in the bottom of the sand box and is welded or otherwise secured to the bottom of the box. The upper end portion of the outlet pipe 18 desirably converges to a smaller diameter thereby facilitating the free 35 flow of sand through the pipe. The upper end of the sand pipe which projects into the sand box above the plate 20 desirably is cut to present an inclined wall 21 of approximately forty-five degrees thereby providing an opening of 40 somewhat greater area than that of the horizontal section through the pipe and also presents an inclined upper edge which will prevent the sand in the sand box from accumulating upon the top of the pipe and bridging it.

45 The closure member for the outlet end of the outlet pipe is in the form of a cup-shaped valve having an arcuate, preferably semi-cylindrical portion 22 which underlies the discharge end of the outlet pipe 18 and is narrowly spaced therefrom and preferably having parallel circular ends 23 concentric with the cylindrical portion 22 of the cup. One of these circular ends 23 desirably is rigidly connected by welding or otherwise to a hub 24 upon the end of a shaft 25 which is journaled in suitable bearings 26 fixedly mounted upon vertical webs 27 which are welded or otherwise secured to the under side of the bottom 6 of the sand box. The shaft 25 is so mounted in said webs that its axis is located such suitable distance 50 above the lower end of the outlet pipe 18 that the arcuate or semi-cylindrical wall of the valve will be spaced narrowly from the lower end of the outlet pipe. The axis of the shaft is so located laterally with respect to the vertical axis of the outlet pipe that when the cylindrical portion of the closure member is swung upwardly to the open position illustrated in Fig. 4 the lower edge of the cylindrical closure member will pass beyond the lower end of the outlet pipe, thereby permitting 55 free flow of sand through the outlet pipe.

65 Preferably the construction is such that when the closure member is swung to open position illustrated in Fig. 4 the opposite or upper edge of the closure member will impinge against the 70

outlet pipe thereby jarring it and by reason of the flexible mounting of the outlet pipe in the bottom of the sand box will cause sufficient vibration of the outlet pipe to discharge any sand which may have accumulated in the outlet pipe, or above it.

Any suitable manually controlled means may be provided for actuating the closure member. In the preferred construction illustrated herein the shaft 25 is provided with a rigid arm 28 which is connected by a link 29 to the core 30 of a solenoid 31 which may be mounted upon any convenient portion of the sand box, but preferably is mounted upon the bottom of the sand box. Where two sand-delivering outlet pipes are employed, as shown in Fig. 2, the arm 28 extends from the shaft 25 midway of its length and the solenoid 31 is mounted upon the bottom of the sand box centrally of the width thereof. The solenoid is enclosed in a suitable casing and a pipe 32 extending upwardly from the casing and through the end or side of the sand box provides a housing for the wires 33 and 34 of an electric circuit leading to the electric battery of the vehicle and a switch in said circuit mounted upon the dash board of the vehicle or any other point convenient to the operator in a usual manner (not shown) provides means for energizing and deenergizing the solenoid, thereby to control the actuation of the closure member or members.

When the closure member or members is or are in position to close the outlet pipe or pipes, as illustrated in Figs. 2 and 3, the weight of the closure member, the arm 28 on the shaft 25, and the solenoid serves to maintain the closure member in closed position, as shown in Figs. 2 and 3. When the solenoid is energized by throwing the switch to complete the circuit through the solenoid the core 30 of the solenoid is drawn upwardly thereby swinging the closure member to the position shown in Fig. 4 so that its then upper edge will impinge upon the outlet pipe and jar it as above described. Obviously if sand accumulated on the pipe is not dislodged by the opening of the valve, the switch can be opened and closed any number of times, thereby causing the solenoid repeatedly to cause the closure member to jar the outlet pipe until the sand flows freely through it.

When the closure member is to be swung to closed position it is merely necessary to de-energize the solenoid circuit by throwing the switch so that the arcuate or cylindrical portion of the closure member will be swung into closed position illustrated in Fig. 3. Inasmuch as the arcuate closure member is out of contact with the lower end of the outlet pipe 18 there will be no impediment to the movement of the closure member to closed position shown in Fig. 3. When in such closed position a small amount of sand will accumulate within the cup-shaped closure member which will effectively stop the flow of sand, but no such accumulation will occur as would in any wise resist the swinging of the closure member to open position.

In order to prevent water from entering the cup-shaped closure member and thereby cause adhesion of particles of sand together, a suitable casing for the closure mechanism is provided. While this may be of any suitable form the plate construction comprises a sheet metal casing 35 having outwardly extending flanges 36 which are welded or otherwise secured to the bottom of the sand box and extend longitudinally thereof and a preferably semi-cylindrical section 37 underlying the cylindrical portion 22 of the closure members and provided with downwardly extending tubular

outlets or nipples 38 in axial alignment with the outlet pipe or pipes 18 and preferably of larger diameter than said outlet pipes. The casing is provided with preferably integral ends 39 and the webs 27 in which the shaft 25 is journaled desirably form partitions which will prevent sand from entering the space between the partitions.

In order to provide for easy assemblage of the closure member upon the sand box and removal therefrom for repair or replacement, the flanged upper ends of the casing desirably are secured by machine screws or bolts to the bottom 6 of the casing.

In order to prevent water from splashing upwardly through the outlets 38 in the casing 36 preferably bell-shaped protectors 40 are secured to the tubular outlets or nipples of the casing. These protectors may be conveniently formed of rubber having cylindrical extensions 41 adapted to clamp upon the extensions or nipples forming outlets of the casing.

In order to support the weight of the sand above the outlet pipe and prevent such compression of the sand adjacent the bottom of the sand box as would interfere with the free flow through the pipe a canopy of much larger area than the diameter of the pipe is mounted directly above the outlet pipe. In the particular construction illustrated the canopy comprises a flat steel plate 42 having an outwardly and downwardly flared peripheral skirt 43 providing an air space beneath the plate 42 which will prevent accumulation of pressure of sand on the upper end of the outlet pipe. The canopy is supported upon a plurality of suitably spaced bolts 44 which extend through the flexible plate 20 and the bottom of the tank and is secured thereto by suitable nuts, the upper end of the bolts 44 being likewise provided with upper and lower nuts on opposite sides of the canopy. By reason of this construction a considerable volume of sand is supported upon the canopy while the spaces between adjacent bolts are sufficient to permit the sand to flow freely inwardly into the inlet end of the outlet pipe 18.

In the operation of the device the sand thus flowing into the outlet pipe 18 will pass downwardly through the outlet pipe 18 and when the closure member is in closed position, as illustrated in Figs. 2 and 3, will accumulate in the cup-shaped closure member sufficiently to block further passage of the sand from the outlet pipe. When it is desired to distribute sand in the path of the traction wheel the switch in the electric circuit is closed thereby to complete the circuit through the solenoid whereupon the solenoid will draw its core upwardly thereby acting through the arm 28 of the shaft 25 to rotate the closure member a quarter turn to the position illustrated in Fig. 4 thus dumping the sand which is accumulated in the cup-shaped closure member and permitting the sand to flow directly from the outlet pipe into the path of the traction wheel. When the electric circuit is interrupted by opening the switch the weight of the cup-shaped closure member, the arm 28 of the shaft, and the solenoid will rotate the closure member to closed position thus shutting off further flow of said from the sand box.

It will be understood that the particular embodiment of the invention shown and described herein is of an illustrative character and is not restrictive, and that various changes in form, construction and arrangement of parts may be made within the spirit and scope of the following claims.

Having thus described the invention, what is claimed as new and desired to be secured by Letters Patent, is:

1. A sanding machine for vehicles comprising a sand box, a vertical outlet pipe flexibly mounted in and extending downwardly from the bottom thereof, a swinging closure member having means to receive and maintain a sufficient accumulation of sand effectively to seal the outlet of said pipe, means normally supporting said closure member in a position in which the accumulated sand will prevent discharge of said from said pipe, actuating means for moving said closure member entirely away from beneath said outlet pipe to a position in which the sand will be wholly discharged from the closure member and unimpeded vertical downward flow of the sand from the outlet of said pipe will be permitted and means operable upon actuation of said closure member to impart vibration to said outlet pipe thereby to dislodge any accumulation of sand which might have occurred therein.

2. A sanding machine for vehicles comprising a sand box, an outlet pipe flexibly mounted in and extending vertically downwardly from the bottom thereof, a semi-cylindrical closure member narrowly spaced from the outlet end of said pipe adapted when in closed position to receive and maintain a sufficient accumulation of sand effectively to seal the outlet of said pipe, pivotal means wholly supporting and entirely guiding said closure member free from external frictional interference, means for swinging said closure member in one direction to discharge substantially all of the sand therefrom and to withdraw one edge of said closure member from beneath the outlet end of said pipe thereby to permit unimpeded flow of sand from said outlet pipe and to cause the opposite edge of the closure member to impinge upon and vibrate said outlet pipe thereby to dislodge any accumulation of sand which may have occurred therein.

3. A sanding machine for vehicles comprising a sand box, a vibratory outlet pipe flexibly mounted in the bottom of said sand box and extending vertically downwardly therefrom, a concavely curved closure member narrowly spaced from the outlet end of said pipe adapted when in closed position to receive and maintain a sufficient accumulation of sand effectively to seal the outlet of said pipe, pivotal means wholly supporting and entirely guiding said closure member free from external frictional interference, and means for swinging said closure member such distance as to discharge substantially all of the sand therefrom and to withdraw one edge of said closure member from beneath the outlet end of said pipe thereby to permit unimpeded flow of sand from said outlet pipe and to cause the opposite edge of said closure member to impinge against and vibrate said outlet pipe.

4. A sanding machine for vehicles comprising a sand box having an outlet pipe extending downwardly from the bottom of the box and flexibly connected thereto, means for controlling the discharge of sand from said pipe comprising a substantially semi-cylindrical closure member narrowly spaced from the outlet end of said pipe pivotally movable about an axis located above the outlet end of said pipe and so spaced laterally from the axis of said pipe as normally to position the closure member beneath said outlet

end and when swung upwardly about its pivotal axis to withdraw one edge of said semi-cylindrical closure member from beneath the outlet end of said pipe and to cause the opposite edge to impinge upon and jar said pipe, and means for actuating said closure member.

5. A sanding machine for vehicles comprising a sand box having an aperture in its bottom, a resilient flexible plate member mounted on said bottom overlying said aperture, an outlet pipe of smaller diameter than said aperture extending substantially centrally through and fixedly secured to said flexible member, a movable closure member for the outlet of said pipe, means for actuating said closure member to permit discharge of sand from said outlet pipe, and means operable upon actuation of said closure member to impart vibration to said outlet pipe.

6. A sanding machine for vehicles comprising a sand box, an outlet pipe mounted in the bottom of the box and projecting substantial distances above and below said bottom with the upper end of said pipe presenting an inclined tubular periphery to prevent choking of the inlet thereof, a closure member for the lower end of said outlet pipe, and means for actuating said closure member to permit discharge of sand from said outlet pipe.

7. A sanding machine for vehicles comprising a sand box, an outlet pipe mounted in the bottom of the box and projecting substantial distances above and below said bottom with the upper end of said pipe presenting an inclined tubular periphery to prevent choking of the inlet thereof, a canopy of larger area than that of said pipe overlying the inlet end thereof and having a downwardly and outwardly extending peripheral skirt, means supporting said canopy at a distance above the end of said pipe so constructed as to permit sand to flow beneath the canopy into the inlet end of said pipe, a closure member for the lower end of said outlet pipe, and means for actuating said closure member to permit discharge of sand from said outlet pipe.

8. A sanding machine for vehicles having a plurality of traction wheels comprising a sand box mounted on said vehicle, vibratory outlet pipes extending through the bottom of said sand box each having a portion thereof flexibly connected to said bottom and positioned to discharge sand in the paths of the respective vehicle wheels, a casting having closed ends mounted upon the under side of said sand box and having downwardly extending tubular portions of greater area than said outlet pipes in alignment with the respective outlet pipes and provided with transverse partitions parallel to and spaced from said ends, a shaft mounted in said partitions laterally offset with respect to a vertical plane passing through said outlet pipes, closure members secured to the ends of said shaft having semi-cylindrical bottoms normally underlying and narrowly separated from the lower ends of said outlet pipes, an arm rigidly mounted on said shaft between said partitions and manually operable means connected to said arm for swinging said closure members from beneath the outlets of said pipe to positions in which the accumulated sand will be discharged from the closure members and the closure members caused to impinge upon and simultaneously vibrate said outlet pipes.

BENJAMIN F. ATWOOD.

CERTIFICATE OF CORRECTION.

Patent No. 2,232,422.

February 18, 1941.

BENJAMIN F. ATWOOD.

It is hereby certified that error appears in the printed specification of the above numbered patent requiring correction as follows: Page 3, second column, line 67, for the word "said" read --sand--; and page 4, first column, line 12, claim 1, for "said" first occurrence, read --sand--; and that the said Letters Patent should be read with this correction therein that the same may conform to the record of the case in the Patent Office.

Signed and sealed this 25th day of March, A. D. 1941.
